(57) **CLAIM**

The ornamental design for a light activated tooth whitening apparatus, as shown and described.

DESCRIPTION

FIG. 1 is a top view of a light activated tooth whitening apparatus showing our new design;

FIG. 2 is a bottom view thereof;

FIG. 3 is a rear view thereof;

FIG. 4 is a front view thereof;

FIG. 5 is a right hand side view thereof; and

FIG. 6 is a left hand side view thereof; and,

FIG. 7 is a perspective view thereof.
